United States Patent

Des. 238,637

Patented Feb. 3, 1976

238,637

GRAB BAR

Hans Arne Valentin Johansson, Eslov, Sweden, assignor
to John Richard Johansson, Eslov, Sweden

Filed May 16, 1974, Ser. No. 470,456

Term of patent 14 years

Int. Cl. D23—02

U.S. Cl. D6—86

FIG. 1 is a bottom plan view of a grab bar, showing my new design;

FIG. 2 is a side elevational view thereof;

FIG. 3 is a top plan view thereof; and

FIG. 4 is an end elevational view thereof.

I claim:

The ornamental design of a grab bar, as shown and described.
